H. M. LEH

BOOKREST

Filed Dec. 4, 1922

Inventor
Harold M. Leh,

by *John Steele Jackson*
Attorney

UNITED STATES PATENT OFFICE.

HAROLD M. LEH, OF PHILADELPHIA, PENNSYLVANIA.

BOOKREST.

Application filed December 4, 1922. Serial No. 604,672.

To all whom it may concern:

Be it known that I, HAROLD M. LEH, a citizen of the United States, residing at Philadelphia, in the county of Philadelphia and State of Pennsylvania, have invented a certain new and useful Bookrest, of which the following is a specification.

My invention relates to book-rests and more particularly to folding rests adapted for use by stenographers when transcribing their notes to the typewriter.

The purpose of my invention is to provide an improved rest of the character indicated that may be at once well adapted to meet the needs of service, that will fold fully, holding a note book in either open or folded position, and that is easy and inexpensive to manufacture.

Further purposes will appear in the specification and in the claims.

I have preferred to illustrate my invention in but one form, selecting a form that efficiently performs the functions required and which moreover well illustrates the principles involved.

In the drawings Figure 1 is a perspective view of my rest when folded.

Figure 2 is perspective view of the same rest open and in position for use.

Figure 3 is a section upon line 3—3 of Figure 1.

Describing in illustration and not in limitation:

In order to fully satisfy the convenience of stenographers a book-rest should be capable of adjustment to a variety of angles, should hold the book firmly and should occupy a minimum of space when in folded position. I have aimed to meet these conditions with a maximum of strength and a simplicity of construction which secures cheapness along with great convenience.

In the illustration, the metal base 8 is padded at 9 with felt to protect the surface of the desk. The metal of the base is upwardly bent presenting edges 10 to prevent rearward movement of a bracket 11 pivoted to the back of a preferably metal supporting flap 12. The bracket is adapted to fold against the flap and may be made to fold either way.

The flap and base are pivoted together at the bottom of the flap and the same pintle

13 is used to pivot a stop 14 by which excessive downward movement of a note book or other copy is prevented. This common pivoting saves in space and in manufacture and the strips of the metal 15 and 16 from the base and stop respectively are oppositely turned to encircle the pintle, as best seen in Figure 3, leaving room for the strips 17 of the flap to pass between them.

Near the upper and lower ends of the flap I provide clips 18 and 19 pivoted to the back of the flap, preferably near enough to the ends to fold against the front of the flap to hold the note book or other copy and about the ends of the flap and of the base in folded position. When folded they will therefore lie against the back of the base or, when desired, against a note book or other copy between them and the back of the base.

The bracket 11 occupies less room across the width of the flap than the entire width and when folded lies between the base and flap.

At the hinge I space the base and flap just sufficiently to leave room for the hinges of the clips and brackets and for the metal edges 10 of the base so that the parts shall fold flat to the position shown in Figure 1.

It will be obvious that the desirable features of my invention may be presented in other forms and it is my purpose to secure herein all such as come within the reasonable spirit and scope of my claims.

Having thus described my invention, what I claim as new and desire to secure by Letters Patent is:—

1. A folding book-rest comprising a base, a supporting flap pivotally secured to the base, a brace between the flap and base and a pivoted bail at the lower end of the flap adapted to fold and hold against the front of the flap or the back of the base.

2. A book-rest comprising a base, a flap and a stop pivoted together and having a common pintle, a brace between the flap and base, adjustable to different slopes of flap and book-holding clips near the upper and lower ends of the flap, adapted to clip and hold against the front of the flap or the back of the base.

3. A collapsible book rest, comprising flap and base members, means for supporting them in extended position and clips mov-

able to clip the copy in front of the book in use and to be shifted back of the base when not in use to hold an object between it and the back.

- 5 4. A collapsible book rest, comprising base and flap members pivoted together, in combination with a bail wider than the flap

member and pivoted to it near enough to the end to fold either way so as to hold the copy in one position and to retain the base 10 and flap members together in the other position.

HAROLD M. LEH.
